UNITED STATES PATENT OFFICE.

CHARLES G. RICHARDSON, OF SPRINGFIELD, VERMONT, ASSIGNOR TO PARKS & WOOLSON MACHINE COMPANY, OF SPRINGFIELD, VERMONT, A CORPORATION OF VERMONT.

CLOTH-STRETCHING ROLLS.

Application filed June 27, 1921. Serial No. 480,682.

To all whom it may concern:

Be it known that I, CHARLES G. RICHARDSON, a citizen of the United States, and resident of Springfield, in the county of Windsor and State of Vermont, have invented certain new and useful Improvements in Cloth-Stretching Rolls, of which the following is a specification.

This invention relates to cloth stretching rolls of the type that are employed for stretching the cloth transversely of its length before the cloth is packaged in bolts or otherwise. The present improvements are intended to provide a device of this class which shall more perfectly perform this operation of stretching cloth transversely, while at the same time freeing it from wrinkles and operating at a minimum expenditure of power.

Cloth stretching rolls may be used in two different ways. First, they may be positively rotated so as to draw the cloth over the roll by the rotation of the roll, or they may operate as idler rolls, rotation being imparted thereto by the travel of the cloth that is drawn over the roll by some other means. In either case the peripheral lags which frictionally engage the cloth and which are moved longitudinally apart for the stretching operation are subjected to tangential or circumferential stress which tends to tilt or tip the lags engaged upon their bearing support and also to axial stress due to the longitudinal pressure or pull exerted for the purpose of stretching the cloth longitudinally of the roll and transversely of the cloth. A careful study of these machines show that the tangential stress, that is, stresses in the direction of the travel of the cloth over the roll cause the individual reciprocating lags to bind on their bearings thereby increasing the resistance to their necessary longitudinal or axial movement, while at the same time imposing much lengthwise strain upon the cloth which tends to neutralize or impair the transverse stretching action which is the main purpose to be accomplished.

The present invention is intended to overcome these difficulties and does so by the utilization of two novel principles of construction and arrangement, the first of these being the mounting of the axially movable lags entirely upon roller contacts by

which the least possible resistance is afforded to the longitudinal movement of the lags in the cloth stretching operation, while the second novel principle embodied is so arranging the bearing supports of the individual lags that the tangential or other stress incurred in the normal operation of the machine is sustained in such a way as to overcome the binding action due to the tangential stress upon the cloth thereby relieving the cloth of much of the strain lengthwise of the cloth, and thereby avoiding the tendency to neutralize or minimize the transverse or stretching action.

This and other features of the invention will be more particularly described in the following specification and will be defined in the claims hereto annexed.

In the accompanying drawings I have illustrated a convenient and practical construction and arrangement which embodies the principles of this invention, in which:

Figure 1 is a side elevation showing the end and middle portion of a cloth stretching roll.

Figure 2 is a longitudinal section on the plane 2—2 of Figure 3.

Figure 3 is an end elevation of the cylinder and lag-actuating head partly broken away.

Figure 4 is an enlarged detail longitudinal section of the end of a single lag showing the relation of the roller contacts to the lag and the actuating head.

Figure 5 is a transverse section showing a single lag mounted on the roller contacts of the central supporting structure.

Figure 6 is a plan view of the same.

Figure 7 is a detail of the cam member.

In the practice of this invention, according to the specific form thereof illustrated in the drawings, I provide a longitudinal central shaft 1 to which is secured a series of lag-supporting spiders 2 arranged to support two cooperating aligned sets of lags 3—3 to permit them to move longitudinally toward and away from each other.

Near its opposite ends each individual lag 3 is provided with a longitudinal recess to form a run-way and in this recess is mounted a bearing track 5 comprising outwardly extending parallel longitudinal flanges 5^a forming, so to speak, a longitudinal or axially extended track for engaging the contact or guide roller which supports the tan-

gential or circumferential stress exerted upon the lag by the pull of the cloth. The track 5 has also inwardly projecting parallel flanges 5^b whose inner ends are turned 5 inwardly toward each other to form retaining lips or flanges 5^c, thus forming a runway or track for rollers which support the radial stress or pressure of the lags.

The supporting spiders 2 are here shown 10 as comprising five radial arms into the outer end of each of which is driven a radial pin 7 and a transverse pin 6. On the radial pin is carried a contact roller 9 whose diameter is slightly less than the space between the 15 two track flanges 5^a. The transverse or tangential pin 6 projects through both sides of this supporting arm 2 to carry on its projecting ends a pair of contact rollers 8 whose diameters are slightly less than the perpendicular distance between the inturned flanges 5^c and the tangential body portion 5 of the bracket, which latter is attached to the lag as shown in Figure 4 by means of 20 screws or the like.

25 As it is very desirable that no rust should be deposited upon the lag it is preferred that the bearing bracket 5 and the contact rollers 8 and 9 should be of rust-less metal such as brass or bronze, and inasmuch as 30 the spiders will ordinarily be made of iron or steel, rustless washers 10 and 11 are interposed between the contact rollers and the adjacent portions of the spider to prevent the deposit of rust upon the rollers.

35 Suitable means may be provided for imparting reciprocatory or axial to and fro movement to each series of lags. The construction herein shown for that purpose comprises a roller carrying bracket 20 secured to the outer end of each lag and carrying a radial pin 21 on which is mounted a rotary roller 22 in a plane tangential to the circle of rotation. This roller is located between parallel peripheral flanges 40 45 14 and 15 of a stationary cam-like head 13 which is mounted in any suitable manner at each end of the cloth stretching roll so as to be held against rotation. In this case the cam head 13 is mounted directly on the shaft 1 and has an interlocking engagement with the stationary roll-supporting standard 18 as shown at 16 so as to hold the actuating cam against rotation. As shown 50 55 in the drawings, this cam forms a roller engaging track whose plane is inclined endwise to the axis or to the path of rotation so that with each revolution of the cloth stretching drum or roll, each pair of axially aligned lags are given one complete in and out stroke or reciprocation longitudinally of the stretch roll. As shown in Figure 2, the heads or track cams oppositely incline to each other so that each one of a cooperating 60 65 pair of lags moves longitudinally in the direction opposite to the movement of the

other so that they may alternately move together and move apart. As is understood by those skilled in the art, the cloth to be stretched comes into contact with successive pairs of lags when the lags are in their 70 inward position near to each other and then during the further revolution of the stretch roll the lags are gradually drawn apart so as to stretch the cloth longitudinally of the roll and transversely of the cloth, the cloth 75 leaving contact with the cylinder at the point where each pair of lags are at their position of greatest extension or separation. In short, the cloth supporting surface of the stretch roll is continuously extended or 80 lengthened over that portion of its periphery with which the cloth is in contact, and is contracted over those portions of the periphery that have lost contact with the cloth. 85

It will be seen that the carrying of the contact roller which supports the tangential stress or pull of the cloth up inside the lag will bring the thrust or strain directly 90 against the anti-friction supporting contact, whereas, if the bearing support for receiving this strain is located well inside the inner surface of the lag, according to practice heretofore, the tangential pull or stress tends to produce a torque or tilting strain on the lag which causes it to bind and 95 greatly increases its resistance to the stretching movement which results in putting additional strain lengthwise of the cloth which means that the lateral stretching action is rendered less effective. Furthermore, the radial pressure or pull of the cloth is supported by rolling contact of the lag upon the rollers that rotate in planes longitudinal of the stretch roll, and when 100 the lags approach their lowermost positions their weight causes them to hang upon the flanges 5^c in contact with the opposite sides of these longitudinal bearing rolls.

105 It will, therefore, be seen that the individual lags are slidingly mounted on a central or interior supporting structure provided with a plurality of supporting and retaining rollers some rotative about tangential axes, and some about radial axes to support, respectively, radial and tangential strains and that the rollers supporting the tangential pull or thrust are carried out well into the lag itself thereby establishing 110 roller contacts substantially in line with and directly opposed to the tangential stresses. 115

120 It will also be observed that the housing rollways forming, so to speak, track portions of the lags act as keepers to keep the rollers from coming off their pins thus dispensing with fastening pins, collars, nuts or the like. The spiders simply have holes to receive radial and tangential pins and when the pins become unduly worn they may be 125 removed and replaced by new pins. 130

The lags may be removed individually from their contact or supporting rolls by sliding them out lengthwise through a gate or opening 15^a in the outer flange 15 of each 5 cam member or head when the spider is revolved to bring the particular lag to be removed in line with said opening. Normally the gateway or gap 15^a may be closed by a detachable plate or section 15^b which is 10 fastened by screws or other suitable means to each cam member.

As cloth is usually stretched in wet condition, the rustless washers 10 and 11 of bronze or equivalent material pressed onto 15 the pins 6 and 7 protect against the spread of rust to the lags and to the cloth. As to the lag-actuating rolls carried at the ends of each lag are entirely beyond the ends of the lag it is not so important that they 20 should be made of rustless material.

What I claim is:

1. In a cloth stretching roll, the combination of an interior revoluble supporting structure, a circumferential series of longitudinally movable lags whose outer surfaces are adapted to form frictional engagement with the cloth being stretched, a series of bearing rollers interposed between individual lags and the adjacent portions of the 25 supporting structure with their several axes of rotation disposed to afford roller contacts to sustain both the radial and the lateral thrusts exerted upon each lag by the tension of the cloth being stretched, substantially as described.

2. In a cloth stretching roll, the combination of a central shaft, lag-supporting spiders projecting therefrom and provided with a series of lag-supporting and guiding 40 rollers mounted at the ends of each spider arm, a series of longitudinally movable lags having bearing engagement with said rollers to support the lags both laterally and radially against circumferential and radial thrust 45 while the stretching roll is in action to stretch the cloth, substantially as described.

3. In a cloth stretching roll, the combination of an interior supporting structure, groups of bearing rollers mounted circumferentially thereon to turn about radial and tangential axes, a series of peripheral lags slidably supported by corresponding groups of rollers so as to have free sliding movement lengthwise of the stretch roll 50 while being held against radial and circumferential stress by said rollers, and means for causing said lags to reciprocate upon said rollers as the stretch roll revolves, substantially as described.

4. In a cloth stretching roll, the combination of a series of peripheral longitudinal lags provided with roller engaging track portions, a revoluble interior supporting structure carrying circumferentially arranged lag supporting rolls having lag sup-

porting and retaining roller contacts with track portions of said lags, and means for causing said lags to move to and fro longitudinally as the stretch roll revolves, substantially as described. 70

5. In a cloth stretching roll, the combination of an interior revoluble lag-supporting structure, a circumferentially arranged series of longitudinal cloth-engaging and stretching lags slidably supported thereon 75 entirely by roller contacts arranged to afford anti-friction support against all transverse stresses to which the lags are subjected by the tension of the cloth being stretched, and cam-engaged rollers exerting endwise thrust on said lags to cause them to reciprocate longitudinally of the stretch roll as the latter revolves, substantially as described.

6. In a cloth stretching roll, the combination of a revoluble shaft, lag carrying spiders mounted thereon, a series of longitudinally movable peripheral lags arranged around said spiders and lag supporting rolls forming intermediate bearing supports between the lags and the spider arranged to sustain the tangential stress exerted on the lags by the pull of the cloth and thereby prevent tilting of the lag laterally, substantially as described. 85

7. In a cloth stretching roll, the combination with peripheral cloth-engaging lags of a revoluble interior supporting structure, peripherally arranged groups of bearing rollers carried thereby to form rolling contact and support for the cloth lags, a series 90 of peripheral cloth lags provided with interior recesses to receive inserted rolls whereby antifriction bearing support is afforded each lag in direct opposition to the tangential stress exerted by the cloth being stretched, substantially as described. 100

8. In a cloth stretching roll, the combination of opposed reciprocatory lags, a revoluble interior supporting structure including radially projecting spiders provided 105 with series of circumferentially disposed roller carrying pins arranged radially and tangentially to the axis of rotation of the supporting structure, a series of housings formed to track against the rollers and also 110 retain the rollers upon their pins, substantially as described.

9. In a cloth stretching roll, the combination of a revolubly interior supporting structure, a circumferentially arranged series of rollers carried thereby, a peripheral series of lags slidably supported by said rollers, said lags being provided with roller engaging housings formed with roller 115 engaging surfaces or tracks arranged on opposite sides of the rollers, whereby the lags are supported and retained against radial movement, substantially as described. 125

10. In a cloth stretching roll, the combination of an interior revoluble supporting 130

- structure, series of circumferentially arranged rollers carried upon two series of pins angularly disposed with relation to each other, and reciprocatory circumferential lags slidingly supported by said rollers against both radial and circumferential thrust, substantially as described.
11. In a cloth stretching roll, the combination of an interior revoluble supporting structure, a circumferential series of reciprocatory lags mounted thereon, a cam like head located adjacent to each end of the stretch roll, each head inclined toward the other, a series of lag actuating rolls connected with said lags in position to engage said inclined heads, each head being provided with a gateway for permitting the removal in an axial direction of the individual lags, substantially as described.
12. In a cloth stretching roll, the combination of a revoluble interior supporting structure, circumferential lags having supporting and retaining connection with supporting structures only by rolling contacts, lag actuating members located at opposite ends of the stretch roll to cause reciprocation of the lags, said actuating members being constructed to permit endwise movement of the lags until the lags are disengaged from retaining connection with the rollers, substantially as described.
13. In a cloth stretching roll, the combination of an interior revoluble supporting structure, series of circumferentially arranged reciprocatory lags, housings secured thereto, each housing being formed with series of roller engaging track portions, one set of tracks located inside the lags themselves and the other set being arranged nearer to the central axis in planes tangential to the axis of rotation, and antifriction rollers mounted on the supporting structure to project between said tracks, substantially as described.
14. In a cloth stretching roll, the combination of an interior revoluble supporting structure, a series of lag supporting rollers circumferentially mounted upon said structure, said rollers being of rustless material, and washers of rustless material interposed between the rollers and the supporting structure, housings provided with roller engaging track members, and lags secured to said housings, substantially as described.

In witness whereof, I have subscribed the above specification.

CHARLES G. RICHARDSON.
